(57) **CLAIM**

The ornamental design for an adult toy as shown and described.

DESCRIPTION

FIG. 1 is a left perspective view of an adult toy showing the claimed design;

FIG. 2 is a right perspective view thereof;

FIG. 3 is a top plan view thereof;

FIG. 4 is a bottom plan view thereof;

FIG. 5 is a left elevation view thereof;

FIG. 6 is a front plan view thereof;

FIG. 7 is a back plan view thereof;

FIG. 8 is a left perspective view of an adult toy according to a second embodiment;

FIG. 9 is a right perspective view thereof;

FIG. 10 is a top plan view thereof;

FIG. 11 is a bottom plan view thereof;

FIG. 12 is a left elevation view thereof;

FIG. 13 is a front plan view thereof; and,

FIG. 14 is a back plan view thereof.

The broken lines shown in the drawings depict portions and controls of the adult toy that form no part of the claimed design.

1 Claim, 10 Drawing Sheets
